BURNER CONTROL APPARATUS

Edward D. Jones and William R. Teller, Cleveland, Ohio, assignors to American Gas Association, Incorporated, New York, N. Y., a corporation of New York

Application October 5, 1933, Serial No. 692,295

9 Claims. (Cl. 158—117.1)

This invention relates to burner control apparatus, and has for an object the provision of mechanism operable automatically to interrupt the supply of fuel to a burner when the flame thereof is accidentally extinguished, and further relates to such mechanism in combination with means for delaying operation in a predetermined manner, more particularly to insure co-action with setting and relighting devices.

10 In the drawings accompanying this specification and forming a part of this application, we have shown, for purposes of illustration, certain forms which our invention may assume.

In these drawings:

15 Figure 1 is a fragmentary top plan view of an embodiment of the invention.

Figure 2 is a vertical sectional view corresponding substantially to the line 2—2 of Figure 1, and showing parts in elevation.

20 Figure 3 is an enlarged fragmentary vertical sectional view, corresponding substantially to the line 3—3 of Figure 1, and showing the parts in one operative position.

Figure 4 is an enlarged fragmentary vertical sectional view, similar to Figure 3, and showing the parts in a different operative position.

Figure 5 is an enlarged fragmentary vertical sectional view corresponding substantially to the line 5—5 of Figure 3, while

30 Figure 6 is a fragmentary vertical sectional view corresponding substantially to the line 6—6 of Figure 4.

The embodiment of the invention illustrated herein comprises a burner 10 formed with a mixing tube 11 of any suitable type, adapted to receive fuel from a nozzle 12, communicating with a valve casing 13, in which is rotatably mounted a tapered plug 14 provided with a handle 15 by which it may be rotated and having a bore 16 adapted to communicate with the nozzle 12 and with a conduit 17 leading to the casing 18 of a valve mechanism 19.

The valve casing 18 is provided with a partition 20 defining an outlet chamber 21 communicating with the conduit 17 and also defining an inlet chamber 22 communicating with a principal source of fuel supply as indicated at 23, and the partition has an opening 24 affording communication between the outlet chamber 21 and inlet chamber 22 and is formed about said opening to provide a valve seat for the reception of a valve member 25 normally urged to closed position by means of a coiled spring 26 interposed between said valve and the adjacent wall of the casing.

55 The valve 25 is provided with a rigid extension 27

which slidably extends through the top wall 28 of a dash-pot receptacle 29 substantially filled with liquid, such as oil, and inside of the receptacle 29, the extension 27 is provided with a piston 30 having a small opening 31 extending laterally therethrough and having a larger opening 32 provided with a valve seat 33 adapted to cooperate with a valve member 34 normally held closed by a leaf spring 35. Secured to the valve 25 and extending outwardly through a packing gland 36 is a 10 valve stem 37, and rigidly secured to the outer end of the valve stem 37, as by a threaded connection 38, is a sleeve 39 having at its terminal end an annular flange 40 and slidably extending into the flanged end of the sleeve 39 is a bearing 15 member 41 rigidly secured as at 42 to the upper wall of an enclosing housing 44 carried by a frame member 45 of the apparatus. The side wall 46 of the housing 44 carries a latching pin 47 adapted in one position of the sleeve 39 to 20 engage beneath the flange 40, and the pin is normally urged in an outward direction by a spring 48 interposed between the head 49 of the pin and the adjacent wall of the housing, and the head of the pin 47 is adapted to be engaged by the free 25 end of a bimetallic thermostatic element 50 affixed to the housing 44 and disposed adjacent to the burner 10, the thermostatic element being so constructed that when heated, as when the burner 10 is burning, it operates to press the latching 30 pin 47 inwardly.

The end of the bearing member 41 projecting into the sleeve 39 is beveled as at 51 for cooperation with the beveled surface 52 of a block 53 carrying a pin 54 projecting outwardly through 35 an aperture in the side wall of the sleeve 39, and the block 53 is carried by a leaf spring 55 which may be secured to the end of the valve stem 37 as at 56, and the spring is so biased as normally to maintain the pin 54 in projected position, yet is yieldable to permit withdrawal of the pin from its projecting position. Slidably mounted upon the sleeve 39 is an outer sleeve 57, and the outer sleeve is provided with a vertically extending rack 58 meshing with a segmental gear 45 59 carried by a shaft 60 extending outwardly through the wall of the housing 44 and being coupled by a coupling 61 with an extension 62 on the rotatable valve member 14, so that rotation of said valve member rotates the shaft 60 and 50 the segmental gear 69.

Disposed adjacent to the burner 10 is a flasher tube 63, which may be of any well known construction, and the flasher tube 63 extends in close proximity to a pilot burner 64 which may receive 55

its fuel supply through a conduit 65 tapped into the main fuel conduit 23.

In operation, and assuming that the main burner 10 is not burning and that the pilot burner 64 is burning, and the operative parts of the apparatus are in the condition illustrated in Figures 2, 3, and 5, the valve member 14 is rotated in a direction which eventually will bring the bore 16 in registration with the nozzle 12 and with the conduit 17, and through the coupling 61, rotary movement of the valve member 14 is transmitted to the shaft 60 and to the gear 59, which engaging the rack 58 will elevate the outer sleeve 57, and by reason of the projection of the pin 54 in the path of movement of the outer sleeve 57, will also elevate the inner sleeve 39, and will continue to elevate the sleeve 39 until the beveled surface 52 on the block 53 comes into engagement with the beveled surface 51 of the bearing member 41, at which time the pin 54 is retracted, and the outer sleeve will overrun the pin, the inner sleeve 39 meanwhile having been elevated sufficiently to bring the flange 40 above the level of the latching pin 47. Elevation of the sleeve 39 causes corresponding elevation of the valve stem 37 and opening of the valve 25, establishing flow of fuel from the main fuel source 23, into the conduit 17, through the bore 16 of the valve member 14 and to the burner 10. During the elevation of the valve stem 37, corresponding elevation is imparted to the piston member 30 through the rigid extension 27 and the liquid in the receptacle 29 above the piston member 30 passes rather freely through the valve opening 32, the valve member 34 during this action being unseated.

The gas thus passing from the main source to the burner then enters the flasher tube 63, is ignited by the pilot burner 64, and flashes back to establish ignition of gas issuing from the burner 10. The heat generated by the burner then begins to deform the thermostatic element 50 rather slowly, and when so deformed, the thermostatic element 50 presses the latching pin 47 inwardly beneath the flange 40 on the sleeve 39, the sleeve meanwhile being retarded against falling, due to the action of the dash-pot arrangement, which on downward movement of the piston member 30, causes closing of the larger opening 32 by the valve member 34, and hence transference of the liquid must take place through the smaller opening 31 resulting in very slow downward movement of the valve stem 37 and sleeve 39, the movement being timed so that the flange does not move sufficiently to drop below the level of the latching pin 47 until after the thermostatic element 50 has moved the latching pin 47 to a position beneath the flange, and the pin of course holds the sleeve elevated so long as the burner 10 is burning and the thermostatic element is deformed.

Should the flame at the burner 10 be accidentally extinguished, before the thermostatic element 50 has cooled and moved sufficiently to release the latching pin 47, the burner will be re-lighted through the flasher tube 63 and pilot burner 64. If, however, the flame at the burner remains extinguished, the thermostatic element 50 again assumes its normal position, releasing the latching pin 47 which is pressed out of engagement by the spring 48, and the sleeve 39 and valve stem 37 begin to descend slowly under the influence of the spring 26, resulting in closing of the valve member 25 and cutting off passage of fuel through the conduit 17, and no fuel will pass

through the valve member 14 even though it remains open. When the rotatable valve member 14 is closed, it will move the outer sleeve 57 downwardly until the pin 54 is again projected, and the parts will be in position for operation as already described. 5

It will be appreciated that the retarded closing movement of the safety valve structure gives ample time for operation of the thermostatic element, and for ignition to be re-established at the burner 10 before the mechanism moves sufficiently to clear the latching pin 47. Furthermore relative movement provided between the sleeves 39 and 57 permits of setting the device through manipulation of the burner cock, permits full opening of the cock and re-setting thereof, in addition to providing for the retarded closing action already described.

It will be apparent to those skilled in the art that the embodiment of the invention herein described accomplishes at least the principal object of our invention, and it will also be apparent that uses and advantages other than those herein referred to are inherent in the construction; it will further be understood that various changes and modifications may be made without departing from the spirit of the invention; consequently it will be understood that the embodiment herein disclosed is illustrative only and the invention is not limited thereto. 30

We claim:

1. Apparatus of the character described, comprising: a burner; a fuel supply conduit for said burner; valve means controlling supply of fuel through said conduit; cooperating members, the first of which is connected to said valve means, and the other of which is relatively movable with respect to said first member; means normally urging said first member in a direction to close said valve means; means retarding closing movement of said valve means; means coupling said members for movement in unison to open said valve means; disengaging means, engageable with said coupling means to disconnect said cooperating members, for relative movement when opening of said valve means is effected; and holding means including means responsive to the change in temperature at said burner when a flame is established thereat, operative to engage said first member during the interval provided by retarded closing of said valve means. 40

2. Apparatus of the character described, comprising: a burner; a fuel supply conduit for said burner; safety valve means controlling supply of fuel through said conduit; cooperating members, the first of which is connected to said valve means, and the second of which is relatively movable with respect to said first member; means normally urging said first member in a direction to close said valve means; means retarding closing movement of said valve means; means coupling said members for movement in unison to open said valve means; disengaging means, engageable with said coupling means to disconnect said cooperating members, for relative movement when opening of said valve means is effected; holding means including means responsive to the change in temperature at said burner when a flame is established thereat, operative to engage said first member during the interval provided by retarded closing of said valve means; a manually controllable valve also controlling the passage of fuel through said fuel supply conduit, having means operable through opening move- 60

ment of said manually controlled valve, engageable with said second member to move the same while said members are coupled to open said safety valve means.

5 3. Apparatus of the character described, comprising: a burner; a fuel supply conduit for said burner; valve means controlling flow of fuel through said conduit; cooperating members, the first of which is connected to said valve means, and the other of which is relatively movable with respect to said first member; means coupling said cooperating members for movement in unison to open said valve means; disengaging means, engageable with said coupling means to disconnect said cooperating members, for relative movement between the same when opening of said valve means is effected; means normally urging said first member in a direction to close said valve means; means retarding closing movement of said valve means; thermostatic means responsive to the change in temperature at said burner; and means, operated by said thermostatic means upon the heating thereof, engaging said first member during the interval provided by the retarded closing of said valve means, to hold the latter open.

4. Apparatus of the character described, comprising: a burner; a fuel supply conduit for said burner; valve means controlling flow of fuel through said conduit; cooperating members, the first of which is connected to said valve means, and the other of which is relatively movable with respect to said first member; means coupling said cooperating members for movement in unison to open said valve means; disengaging means, engageable with said coupling means to disconnect said cooperating members, for relative movement between the same when opening of said valve means is effected; means normally urging said first member in a direction to close said valve means; hydraulically controlled mechanism for retarding closing movement of said valve means; thermostatic means responsive to change in temperature at said burner; and means, operated by said thermostatic means, engaging said first member during the interval provided by the retarded closing of said valve means, to hold the latter open.

5. Apparatus of the character described, comprising: a burner; a fuel supply conduit for said burner; valve means controlling flow of fuel through said conduit; cooperating sleeve members, the first of which is connected to said valve means, and the second of which is relatively movable with respect to said first sleeve member; means carrying a detent, coupling said sleeve members, for movement in unison to open said valve means; disengaging means, engageable with said detent, when opening of said valve means is effected, for disconnecting said cooperating sleeve members for relative movement between the same, to permit movement of said valve means to closed position; means normally urging said first member in a direction to close said valve means; mechanism retarding closing movement of said valve means; a thermostat responsive to the change in temperature at said burner; and latch means, engageable with said first member and said thermostat, operated by the latter to engage said first member during the interval provided by the retarded closing thereof to hold said valve means open.

6. Apparatus of the character described, comprising: a burner; a fuel supply conduit for said

burner; safety valve means controlling flow of fuel through said conduit; cooperating members, the first of which is connected to said safety valve means, and the second of which is relatively movable with respect to said first member; motion transmitting means carried by said second member; means coupling said cooperating members for movement in unison to open said safety valve means; disengaging means, engageable with said coupling means to disconnect said cooperating members, for relative movement between the same when opening of said safety valve means is effected; means normally urging said first member in a direction to close said safety valve means; means retarding closing movement of said safety valve means; thermostatic means responsive to the changes in temperature at said burner; and means, operated by said thermostatic means, engaging said first member during the interval provided by the retarded closing of said valve means, to hold the latter open; and a manually controllable valve also controlling the flow of fuel through said fuel supply conduit, and having motion transmitting means, operable through opening movement of said manually controlled valve, to engage said motion transmitting means on said second member to effect movement of said coupled members to open said safety valve means.

7. Apparatus of the character described, comprising: a burner; a fuel supply conduit for said burner; safety valve means controlling flow of fuel through said conduit; cooperating members, the first of which is connected to said safety valve means, and the second of which is relatively movable with respect to said first member; means coupling said cooperating members for movement in unison to open said safety valve means; disengaging means, engageable with said coupling means to disconnect said cooperating members, for relative movement between the same when opening of said safety valve means is effected; means normally urging said first member in a direction to close said safety valve means; hydraulically controlled means retarding closing movement of said safety valve means; thermostatic means responsive to the change in temperature at said burner; means, operated by said thermostatic means, engaging said first member during the interval provided by the retarded closing of said valve means, to hold the latter open; and a manually controllable valve also controlling the flow of fuel through said fuel supply conduit, operable through opening movement of said manually controlled valve, to engage said second member to effect movement of said coupled members to open said safety valve means.

8. Apparatus of the character described, comprising: a burner; a fuel supply conduit for said burner; valve means, for controlling fuel to said burner; means normally urging said valve means to closed position; mechanism for retarding closing movement of said valve means; thermostatic means, responsive to the changes in temperature at said burner; cooperating members, the first of which is connected to said valve means and to said retarding mechanism, and the second of which is relatively movable with respect to said first members; means coupling said members for movement in unison during a predetermined part of their travel, for moving said valve means to open position; means disconnecting said members to provide for relative movement with respect to each other, so that said valve means may be urged to closed position in a movement retarded manner; and means operated by said

thermostatic means, when said burner is burning, for engaging said first member when the same is uncoupled from said second member and during the interval provided by the retarded closing 5 of said valve means, and to hold the same open, and being operable to disengage said first member when the flame at the burner is extinguished to permit the closing of said valve means.

9. Apparatus of the character described, comprising: a burner; a fuel supply conduit for said burner; manually operable valve means controlling the flow of fuel to said burner; automatic valve means, controlling the flow of fuel to said manually operated valve means; means normally 10 urging said automatic valve means to closed position; mechanism for retarding closing movement of said automatic valve means; thermostatic means, responsive to the changes in temperature at said burner; cooperating members, 15 the first of which is connected to said automatic valve means and to said retarding mechanism, and the second of which is relatively movable 20 with respect to said first member; means cou-

pling said members for movement in unison during a predetermined part of their travel for moving said automatic valve means to open position, said unison movement being effected by the initial opening of said manually controlled valve; means disconnecting said members when said manually controlled valve has been opened to provide for relative movement of said members with respect to each other, so that said automatic valve means may be urged to closed position in a movement retarded manner, said disconnection providing for free movement of said manually controlled valve without affecting said automatic valve; and means operated by said thermostatic means, when said burner is burning, 15 for engaging said first member during the interval provided by the retarded closing of said valve means, and to hold the same open, and being operable to disengage said first member when the flame at the burner is extinguished to permit the closing of said automatic valve means.
